UNITED STATES PATENT OFFICE.

ROBERT S. FRARY AND WALTER W. MACFARREN, OF PITTSBURGH, PENNSYLVANIA.

SASH-HOLDER.

1,102,489.

Specification of Letters Patent. Patented July 7, 1914.

Application filed February 5, 1913. Serial No. 746,333.

To all whom it may concern:

Be it known that we, ROBERT S. FRARY and WALTER W. MACFARREN, citizens of the United States, residing at Pittsburgh, in the 5 county of Allegheny, State of Pennsylvania, have invented certain new and useful Improvements in Sash-Holders, of which the following is a specification.

Our invention relates to sash holders for 10 windows, and has for its objects to provide a device of this character which allows the sash to be readily moved up or down, and to be adjusted to any desired height, which holds it securely against rattling, and which 15 is simple and inexpensive in construction and easily applied.

Referring to the drawings;—Figure 1 is a vertical section through a portion of a window frame and its associated sash showing side elevation of our improved sash holder in operative position. Fig. 2 is an elevation of the spring. Fig. 3 is an end elevation of the fluted roller. Fig. 4 is a side elevation of the same. Fig. 5 is a side 25 elevation of the pawl. Fig. 6 is an end elevation of the same. Fig. 7 is a side elevation of a portion of the spring showing a modified form of lug attached thereto. And Fig. 8 is a cross section through the spring 30 and its lugs showing the method of inserting the roller.

The window frame 1 is provided with a thin working strip 2, preferably made of vulcanized fiber or similar non-metallic material which is not affected by the weather.

The sash 3 is provided with a recess 4, this recess being somewhat less than the thickness of the sash as will be readily understood, and within this recess we mount 40 our improved sash holder, which consists of three main elements, a bowed spring 5, a fluted roller 6, and a pivoted pawl 7. The spring 5 may be stamped from sheet steel of proper quality, and may be of uniform thickness throughout, or it may be of tapering section, being thicker in the middle.

The spring 5 is provided with a flange 8 at its upper end which abuts against the upper surface 9 of the recess 4. At the 50 upper end of the spring just below the flange 8 a hole 10 is formed, and at the lower end of the spring there is an elongated hole or slot 11. Screws 12 and 13 fasten the spring to the sash. A pair of lugs 14 are formed 55 on the middle portion of the spring and are preferably integral therewith. Each lug 14

is provided with an upper hole 15 and a lower hole 16, these holes being opposite each other in the adjacent lugs.

The roller 6 is provided with integral 60 journals 17 for which the holes 16 form bearings. The pawl 7 is provided with similar journals 18, for which the holes 15 form bearings.

In the manufacture of the spring 5 one 65 of the lugs 14^a is bent to a right angle with the body of the spring, and the opposite lug 14^b is bent to such a position that the journal 17 of the roller 6 can be inserted in the hole 16 before the finishing bend is given to the 70 lug 14^b. The journals 18 of the pawl 7 are engaged by the holes 15 at the same time.

The roller 6 is provided with fluted or grooved surface as shown at 19. These grooves are formed with a radial side 20 75 and a curved portion 21 which connects with the cylindrical surface 22 of the roller. As flutes 22 are comparatively small and few in number the smooth action of the roller is not interfered with. It will be noted by 80 reference to Fig. 1 that the parts are so assembled that one of the portions 22 of the cylindrical surface of the roller bears against the working strip 2 when the pawl 7 engages one of the flutes 19 so that the sash 85 can be moved downwardly without any scraping action being produced by the roller 6 on the working strip 2.

In Fig. 7 we have shown a portion of the spring 5 and a modified form of lug 23, 90 there being two of these held together by a connecting piece 24, the same being connected to the spring 5 by rivets 25. While this construction serves the same purpose as the one shown in Fig. 1, it is more expensive to make and only of advantage when very heavy springs are to be employed. In Fig. 2 we have shown in dotted lines the outline of the lugs 14 as they are punched from the sheet before being bent. It will be observed that by forming the lugs 14 integrally with the springs 5, and by forming 95 integral journals on the roller 6 and the pawl 7, that the entire device with the exception of the fastening screws is composed 100 of only three parts, and is so assembled that the parts cannot under ordinary circumstances become detached or alter their relation with each other.

The use of a fiber working strip insures 110 a uniform smooth track, having a surface well adapted for the frictional engagement

of the roller in that it has a high co-efficient friction and is possessed of the faculty of deadening sound to a considerable extent.

The device is therefore seen to be well adapted to the purpose in view, and to be simple, efficient, durable and inexpensive. The flange 8 forms an ample bearing surface against the wooden sash and prevents the screw 12 from being overloaded.

10. We claim as our invention,

1. A sash holder comprising a bowed spring adapted to be secured to the sash in a recessed portion thereof, lugs carried by said spring, two sets of holes in said lugs, 15 a fluted roller provided with integral journals engaging one set of holes, and a pawl also provided with integral journals engaging the other set of holes.

2. A sash holder comprising a bowed spring adapted to be secured to the sash in a recessed portion thereof, lugs formed integral with said spring and projecting therefrom, a fluted roller carried by said lugs, and a pivoted pawl also carried by 25 said lugs and engaging said roller.

3. A sash holder comprising a bowed spring adapted to be secured to the sash in

a recessed portion thereof, a roller carried by said spring for engaging the window frame, a pawl carried by said spring to 30 prevent rotation of the roller in one direction, and a flange formed on the upper end of said spring to abut against the upper surface of the recess in the sash.

4. A sash holder comprising a bowed 35 spring adapted to be secured to the sash in a recessed portion thereof, outwardly and upwardly extending lugs carried by said spring, and a roller and a pawl carried by said lugs.

5. A sash holder comprising three members, viz., a roller, a pawl and a spring, said roller and said pawl being mounted on said 40 spring, and means for securing the device to a window sash.

In testimony whereof we hereunto affix our signatures in the presence of two witnesses.

ROBERT S. FRARY.
WALTER W. MACFARREN.
